S. SMITH

PICK-UP AND CENTERING DEVICE FOR BILLET HANDLING MACHINES

Filed March 26, 1926

UNITED STATES PATENT OFFICE.

SYDNEY SMITH, OF LONDON, ENGLAND, ASSIGNOR TO THE WELLMAN-SEAVIER-MORGAN COMPANY, OF CLEVELAND, OHIO, A CORPORATION OF OHIO.

PICK-UP AND CENTERING DEVICE FOR BILLET-HANDLING MACHINES.

Application filed March 26, 1926. Serial No. 97,537.

This invention relates to billet handling machines and more especially to machines for transferring billets from a heating furnace to a piercing machine wherein the billet 5 is converted into a tubular blank from which seamless drawn tubing is manufactured.

It is one of the objects of this invention to provide the handling mechanism with means for automatically making a central depression in one or both ends of the billet so as to facilitate the succeeding piercing operation. It is necessary that the depression or depressions, referred to, be accurately located in the ends of the billets and it is a further object 15 of the invention to provide adjustable mechanism for forming these depressions which will accommodate the apparatus to billets of different diameters and of different lengths.

20 Other objects of the invention and the features of novelty will be apparent from the following description taken in connection with the accompanying drawings, of which:

25 Fig. 1 is an elevation of an apparatus embodying my invention;

Fig. 2 is a view similar to Fig. 1, but omitting a portion of the apparatus illustrated in the latter, and having certain parts 30 shown in section and other parts in a different operating position from that shown in Fig. 1; and

Fig. 3 is a section on the line 3—3 of Fig. 1.

35 Referring to the drawings, 10 indicates, generally, the trolley of an overhead crane of the type that is commonly used in steel mills for handling ingots and billets, the trolley 10 being adapted to move back and forth on a travelling bridge of which the beams 11 and 12 are a part. The trolley 10 is provided with wheels 12' which run on rails 13 on the beams 11 and 12. The type 40 of crane which I prefer to employ is that commonly used for handling ingots in connection with soaking pits, such cranes being usually provided with a vertical mast 14, which may be raised and lowered and also revolved, by suitable mechanism forming no 45 part of the present invention.

In accordance with the present invention, I provide, at the lower end of the mast 14, a member 15 on which the brackets 16 and 17 are horizontally adjustable, these brackets 50 engaging with gibbs 18 on opposite sides of

the member 15. Horizontal screws 19 and 20 are arranged in the member 15 and held against endwise movement by the abutting collars 21 which are located between the walls 22. The screw 19 has threaded engagement with a fulcrum member 23 which is horizontally movable in ways 24, in the member 15. In a similar manner, the screw 20 has threaded engagement with a fulcrum member 25 that is horizontally slidable in ways 26 in the member 15. The member 23 is provided with trunnions 27 on which a pair of levers 28 is fulcrumed and the member 25 has trunnions 29 on which a pair of levers 30 is fulcrumed.

The bracket 16 is provided with a cylindrical bore 31 in which the hub 32 of a conical cup-shaped member 33 is slidable. A pin 34 is secured to the bracket 16, by a nut 35, or any other suitable manner, and is arranged co-axial with the hub 32 and surrounded by a spring 36 which is adapted to permit the member 33 to yield when it engages with the end of a billet. A slot 37 extends longitudinally of the hub 32 and the end of a screw 38 engages with this slot so as to prevent the member 33 from turning, although permitting it to move in an axial direction. The inner end of the pin 34 is provided with a conical punch 39 which is arranged at the axis of the pin so as to be adapted to engage the end of the billet and form a depression at the center thereof, this depression serving as a means for locating the piercing tool when the billet is subsequently pierced.

Opposed to the member 33 is a similar member 40 which is slidable in the bracket 17 and backed up by a spring similar to the spring 36. The bracket 16 has a pair of oppositely projecting trunnions 41 to which the lower ends of the levers 30 are respectively connected by links 42, it being understood that these links are arranged on opposite sides of the bracket 16. In a similar manner, the bracket 17 has a pair of oppositely projecting trunnions 42' which are connected with the lower ends of the levers 28 by links 43. A cross-head 44 is vertically slidable in the ways 45, in the mast 14, and this cross-head has oppositely projecting trunnions 46, each of which is connected with the upper ends of the levers 28 and 30 by means of the links 47 and 48, so that the movement of the cross-head 44 actuates

the levers 28 and 30 and thus moves the brackets 16 and 17 toward and away from each other for the purpose of clamping or releasing a billet.

5 A vertically extending shaft 49 is secured to the cross-head 44 and has its upper end threaded, as indicated at 50, and engaged by a rotatable nut 51 which is carried by the frame of the trolley and rotated by 10 means of the gearing 52, from any suitable source of power, such as a motor carried by the trolley.

The bracket 17 carries a pin 53, similar to the pin 34 and having a punch 54 on the 15 inner end thereof to form a central depression in the end of the billet.

In Fig. 2, a billet is indicated in dotted lines at 55 and, when it is desired to lift this billet and form the central depressions in 20 the ends thereof, the parts of the mechanism will be positioned substantially as shown in this figure. The billet will, of course, be supported in such a manner as to permit the members 33 and 40 to receive the ends 25 thereof. The nut 51 is then rotated and the cross-head 44 is thereby raised. The levers 28 and 30 are thus swung toward the positions shown in Fig. 1, the ends of the billet being gripped by the members 33 and 40, 30 which, on account of their conical form, will accurately center the billet. When the members 33 and 40 engage the end of the billet, their movement is arrested and the further movement of the brackets 16 and 17, 35 due to further raising of the cross-head 44, will cause the spring 36 and also the spring which backs up the member 40, to be compressed until the punches 39 and 54 engage the ends of the billet and form the 40 depressions therein. The engagement of the ends of the pins 34 and 53, with the ends of the billet, will arrest the inward movement of the brackets 16 and 17 and the billet will then be gripped in such a manner 45 that it may be lifted and transported to its destination. The conical shape of the members 33 and 40 adapts them to billets of different diameters and, by moving the cross-heads 23 and 25, in or out, as may be necessary, the mechanism may be adapted to billets of different lengths, such movement of the cross-heads being effected by 50 means of the screws 19 and 20.

When it is desired to form a central depression in only one end of the billet, the punch 54 may be omitted.

Having thus described my invention, what I claim is:

1. In apparatus of the class described, the 60 combination of a lifting member, and arm thereon having means adapted to engage one end of a billet, a bracket slidable on said member axially of the billet, a centering member carried by said bracket and engageable with one end of the billet to position the latter, a

punch carried by said bracket and movable therewith to form a central depression in said end of the billet, and means for moving said bracket.

2. In apparatus of the class described, the 70 combination of a lifting member, an arm thereon having means adapted to engage one end of a billet, a bracket slidable on said member axially of the billet, a centering member carried by said bracket and engageable with one end of the billet to position the latter, a punch carried by said bracket and movable therewith to form a central depression in said end of the billet, a 75 lever fulcrumed on said member and operatively connected with said bracket, a vertically movable cross-head on said member, and a link connecting said cross-head and said lever.

3. In apparatus of the class described, the 80 combination of a lifting member, an arm thereon having means adapted to engage one end of a billet, a bracket slidable on said member axially of the billet, a conical cup carried by said bracket and adapted to engage and position one end of a billet, said cup being movable on said bracket and yieldingly held in engagement with the billet, a punch supported within said cup at the axis thereof and adapted to engage the end 85 of the billet and form a central depression therein, and means for moving said bracket.

4. In apparatus of the class described, the 90 combination of a lifting member, an arm thereon having a conical cup adapted to engage one end of a billet to position the same, a bracket slidable on said member axially of the billet, a conical cup slidable on said bracket and adapted to engage and position the other end of the billet, a spring for 95 pressing said cup toward said billet, a punch carried by said bracket and relative to which the second-mentioned cup moves, and means for moving said bracket.

5. In apparatus of the class described, the 100 combination of a lifting member, a pair of opposed brackets slidable on said member, a conical cup member yieldingly carried by each of said brackets and adapted to cooperate to engage the opposite ends of a billet to 105 position the latter, a punch carried by one of said brackets and adapted to engage the end of the billet and form a central depression therein, and means for moving said brackets.

6. In apparatus of the class described, the 110 combination of a lifting member, a pair of opposed brackets slidable on said member, a conical cup member yieldingly carried by each of said brackets and adapted to cooperate to engage the opposite ends of a billet to 115 position the latter, a punch carried by one of said brackets and adapted to engage the end of the billet and form a central depression therein, levers pivotally mounted on 120

125

said lifting member and operatively connected at one end with said brackets, a vertically movable member, and links connecting the last-mentioned member with said levers.

7. In apparatus of the class described, the combination of a lifting member, a pair of opposed brackets slidable on said member, a conical cup member yieldingly carried by each of said brackets and adapted to cooperate to engage the opposite ends of a billet to position the latter, a punch carried by one of said brackets and adapted to engage the end of the billet and form a central depression therein, levers pivotally mounted on said lifting member and operatively connected at one end with said brackets, a vertically movable member, links connecting the last-mentioned member with said levers, and means for adjusting the fulcrums of said levers to adapt the apparatus to billets of different lengths.

8. In apparatus of the class described, the combination of a lifting member, a pair of opposed brackets slidable on said member, a conical cup member yieldingly carried by each of said brackets and adapted to cooperate to engage the opposite ends of a billet to position the latter, a punch carried by one of said brackets and adapted to engage the end of the billet and form a central depression therein, fulcrum members movably mounted on said lifting member, levers pivotally mounted on said fulcrum members and operatively connected at one end with said brackets, a vertically movable cross-head carried by said lifting member, links connecting said cross-head with said levers, and means for adjusting said fulcrum members.

In testimony whereof, I hereunto affix my signature.

SYDNEY SMITH.
